LOUNGE CHAIR

Stanley P. Nash, Wheaton, Ill., assignor to Mohasco
Industries Inc., Amsterdam, N.Y.

Filed Jan. 12, 1970, Ser. No. 20,883

Term of patent 14 years

Int. Cl. D15—01

U.S. Cl. D6—1

The figure is a front perspective view of a chair showing my new design. The back of the chair is conventionally plain while the side not shown is a mirror image of the side shown except for the omission of the handle.

I claim:

The ornamental design for a lounge chair, substantially as shown and described.
